UNITED STATES PATENT OFFICE

MATTHEW F. DESMOND, OF BURLINGAME, CALIFORNIA

LUGGAGE CLAMP

Application filed September 12, 1930. Serial No. 481,537.

My invention relates to improvements in luggage clamps, and it consists in the combinations, constructions and arrangements hereinafter described and claimed.

5 An object of my invention is to provide a luggage clamp that is especially designed to be removably secured to the fender of an automobile and to hold a rope so that the rope can be secured to a package for holding the latter to the automobile. The device is extremely simple in construction and comprises but two parts.

Other objects and advantages will appear as the specification proceeds, and the principal features of the device will be particularly pointed out in the claims hereto annexed.

My invention is illustrated in the accompanying drawings, in which:

20 Figure 1 shows the device operatively applied to a car fender,

Figure 2 is a rear elevation of the device,

Figure 3 is an end view, and

25 Figure 4 is a perspective view of one of the parts.

In carrying out my invention I provide a member 1 that has a tongue 2 cut therein, the tongue extending in the manner shown in Figure 3. The tongue provides the member 1 with two leg portions 3 that have their lower ends connected together by an integral crosspiece 4. The tongue 2 projects through a slot 5 formed by the leg portions 3.

The legs 3 are bent in the manner shown 35 in Figure 3 and are designed to encircle the beaded edge 6 of an automobile fender 7. The curved portions 8 of the legs 3 engage with the inner surface of the bead 6, while the tongue 2 yieldingly engages with the 40 outer surface. The tongue is so bent as to tend to swing toward the curved portions 9 of the legs 3, and thus to free the part 1 from the automobile fender.

I provide means for clamping the fender 45 between the tongue 2 and the legs 3. This means comprises a second member 10 of the shape shown in Figure 4. It will be noted that the member 10 has a curved top 11, recesses 12, a reduced portion 13, and an enlarged transversely extending portion 14

bent substantially at right angles to the plane of the body portion 10. This piece is designed to be inserted in the slot 5 and then to be swung so as to cause the reduced portion 13 to be received in recesses 15 in the slot 5 (see Figure 2).

In inserting the member 10 in the slot 5, the member 1 is preferably held in the left hand with the curved portions 8 resting in the palm of the hand. The member 10 is held in the right hand and then is moved toward member 1 so that the portion 14 extends substantially parallel with the length of the slot 5. The portion 14 is kept parallel with the slot until it has moved past the slot. Further movement in the same direction will cause the recesses 12 to be moved into the same plane with the edges of the slot 5. The member 10 may now be rotated so as to cause the recesses 12 to receive the edges of the slot 5. The member 10 may now be moved along the slot until the portion 13 comes opposite the recesses 15, whereupon the tension of the tongue 2 will cause the edges of the portion 13 to be received in the recesses 15. The device is now ready for use.

From the foregoing description of the various parts of the device, the operation thereof may be readily understood.

The device is placed in any position desired along the fenders and is clamped to the fenders by the swinging of the member 10 into the full line position shown in Figure 3. This movement causes the portion 14 to pivot on the legs 3 and to move the tongue 2 toward the fender 7.

A rope 16 is passed beneath the curved portion 11 in each hook and is secured to the article 17 such as, for example, a suitcase shown in Figure 1. The pull of the rope on the curved portion 11 is in such a direction as to tend to hold the device in locked position.

The member 10 is swung beyond dead center when moved into closed position. This prevents the accidental opening of the clamp. Moreover, the member 10 has the hook-shaped portion 11 so placed that any pull upon this portion from the rope 16 will tend to hold the member in locked position.

Although I have shown and described one

embodiment of my invention, it is to be understood that the same is susceptible of various changes, and I reserve the right to employ such changes as may come within the scope of the invention as claimed.

5 I claim:

- 10 1. A luggage clamp comprising a member having leg portions for engaging with one side of a fender and a tongue portion for engaging with the opposite side, and a second member for locking the tongue against movement.
- 15 2. A luggage clamp comprising a member having leg portions for engaging with one side of a fender and a tongue portion for engaging with the opposite side, and a second member for locking the tongue against movement, said second named member having a hook-shaped portion for receiving a rope, the
- 20 20 hook-shaped portion being placed where the pull of the rope will tend to keep the second member in locked position.
- 25 3. A luggage clamp comprising a member having a tongue and a slot, the slot having opposed recesses in its edges, and a second member fulcrumed on the edges of the recesses and engaging with the tongue for preventing its movement into inoperative position.
- 30 4. A luggage clamp comprising a member having one end curved for engaging with one side of a support, a tongue carried by said member and designed to contact with the opposite side of the support, and a second member pivoted to the first and having a portion engaging with the tongue for preventing its movement into inoperative position when the second member has been swung into closed position.
- 35 5. A luggage clamp comprising a member having a U-shaped end and a slot, a tongue carried by said member and projecting through the slot, a second member having a portion extending through the slot and a second portion engageable with the first member and with the tongue for holding the latter against movement, the opposite end of the second member being hook-shaped for receiving a rope.
- 40 50 Signed at Burlingame in the county of San Mateo and State of California this 6th day of September A. D. nineteen hundred thirty.

55 MATTHEW F. DESMOND.
